(57) **CLAIM**

The ornamental design for a rotary tool, as shown and described.

DESCRIPTION

FIG. 1 is a perspective view of a first embodiment of a rotary tool showing our new design;

FIG. 2 is a right side elevational view showing the design for the rotary tool of FIG. 1;

FIG. 3 is a left side elevational view showing the design for the rotary tool of FIG. 1;

FIG. 4 is a front elevational view showing the design for the rotary tool of FIG. 1;

FIG. 5 is a rear elevational view showing the design for the rotary tool of FIG. 1;

FIG. 6 is a top plan view showing the design for the rotary tool of FIG. 1; and

FIG. 7 is a bottom plan view showing the design for the rotary tool of FIG. 1.

FIG. 8 is a perspective view of a second embodiment of a rotary tool showing our new design;

FIG. 9 is a right side elevational view showing the design for the rotary tool of FIG. 8;

FIG. 10 is a left side elevational view showing the design for the rotary tool of FIG. 8;

FIG. 11 is a front elevational view showing the design for the rotary tool of FIG. 8;

FIG. 12 is a rear elevational view showing the design for the rotary tool of FIG. 8;

FIG. 13 is a top plan view showing the design for the rotary tool of FIG. 8; and,

FIG. 14 is a bottom plan view showing the design for the rotary tool of FIG. 8.

The broken lines shown in the drawings illustrate portions of the rotary tool that form no part of the claimed design.

1 Claim, 12 Drawing Sheets
